UNITED STATES PATENT OFFICE

146,132

DESIGN FOR A DOLL

Dona Jo Curran, Hinsdale, Ill.

Application April 24, 1946, Serial No. 128,925

Term of patent 14 years

(Cl. D34—4)

To all whom it may concern:

Be it known that I, Dona Jo Curran, a citizen of the United States, residing in the village of Hinsdale, county of Du Page, State of Illinois, have invented a new, original, and ornamental Design for a Doll, of which the following is the specification, reference being made to the accompanying drawing, forming a part thereof.

Fig. 1 is a front elevational view of a doll, showing my new design; and

Fig. 2 is a side elevational view of the same.

I claim:

The ornamental design for a doll, as shown.

DONA JO CURRAN.
